US0D1104176S

(12) **United States Design Patent** (10) Patent No.: **US D1,104,176 S**
(45) Date of Patent: ** Dec. 2, 2025

(54) **WEIGHT PLATE**

(71) Applicant: **NEWTECH WELLNESS CO., LTD.**,
Gimhae-si (KR)

(72) Inventor: **Hyun Jung Byun**, Busan (KR)

(73) Assignee: **NEWTECH WELLNESS CO., LTD.**,
Gimhae-si (KR)

(**) Term: **15 Years**

(21) Appl. No.: **29/947,766**

(22) Filed: **Jun. 17, 2024**

(30) **Foreign Application Priority Data**

Dec. 21, 2023 (KR) 30-2023-0052387

(51) **LOC (15) Cl.** **21-02**

(52) **U.S. Cl.**

USPC **D21/680**

(58) **Field of Classification Search**

USPC D21/694, 662, 684, 675, 677, 681, 682,
D21/683, 756, 774, 807, 680, 679

CPC A63B 21/072

See application file for complete search history.
